UNITED STATES PATENT OFFICE.

ERNEST J. QVARNSTROM, OF ATTLEBORO, MASSACHUSETTS, ASSIGNOR TO CARTER, QVARNSTROM & REMINGTON, A FIRM COMPRISING MILES L. CARTER, ERNEST J. QVARNSTROM, AND EDGAR A. REMINGTON, ALL OF ATTLEBORO, MASSACHUSETTS.

ADJUSTABLE NECK-CHAIN.

Specification of Letters Patent.

Patented Jan. 12, 1915.

1,124,518.

Application filed December 15, 1913. Serial No. 806,759.

To all whom it may concern:

Be it known that I, ERNEST J. QVARNSTROM, a citizen of the United States, residing at Attleboro, in the county of Bristol and State of Massachusetts, have invented 5 certain new and useful Improvements in Adjustable Neck-Chains, of which the following is a specification, reference being had therein to the accompanying drawing.

10 This invention relates to adjustable neck chains.

It is found in practice highly desirable to provide an adjustment for ornamental neck chains from which a watch, locket, or the like is suspended, as almost every wearer requires or desires a different length, that is, stout and large persons require a longer chain than slim or small persons, and each 15 desire to adjust the chain to suit her own fancy, whereby the suspended ornament 20 may be supported in the desired position on the person.

To accomplish the above object I have provided a neck chain which has a portion 25 doubled upon itself and the doubled end slidably connected to the adjacent portion of the chain with a member which is adapted to grip and bind or be slid along the chain as may be desired, for the purpose of 30 adjusting the operating length thereof, so that the chain may be regulated to suit the requirements of the wearer.

With these and other objects in view, the invention consists of certain novel features of construction, as will be more fully 35 described and particularly pointed out in the appended claim.

Of the accompanying drawings: Figure 1— is a view illustrating the chain with 40 a portion passed through the ring in one end doubled back upon itself and adjustably connected to another portion of the chain. Fig. 2— is an enlarged view illustrating the doubled portion of the chain as secured 45 by means of a ball shaped gripper. Fig. 3— is an enlarged sectional view of the ball form of gripping member.

Referring to the drawings, 10 designates the neck chain, which may be made of such 50 material as ribbon, cord, chain, beads, or other suitable material adapted to suspend an ornament, or other device, from the neck

of the wearer, all of which for convenience I designate as "chain".

To one end of the chain I preferably attach a ring or loop 11, and the opposite end of the chain is passed through this ring, doubled back upon itself and attached to a binding or gripping member 12, through a hole in which member the adjacent portion 13 of the chain passes, whereby the said binding member is adapted to be slid along the chain, either toward or from the ring 11, so as to lengthen or shorten the double portion of the chain and so regulate or adjust 65 the operating length of the whole.

One form of gripping member is best illustrated in Fig. 3 which comprises a bar 14, having an eye 15 at one end through which the chain passes and an eye 16 at the 70 opposite end in which the end 17 of the chain is secured. It will be noted that by this construction when the bar is brought around into a position at substantially a right angle to the axis of the chain, that 75 it may be readily slid along on the chain, that is, the chain will pass readily through the eye thereof, but when the shank of this member is drawn down substantially in line with or against the chain, as is the case 80 when the chain is under tension, the thickness of the bar serves to clamp, bind and grip the chain and prevent the member from being readily slid along thereon. Substantially the same effect is produced by the 85 binding member when made in the form of a ball or sphere 18, which in practice is the preferred form, the ball having a hole 19 through which the portion 13 of the chain passes. The inside of the ball is preferably 90 filled with cork, or other suitable yieldable or flexible material, adapted to slightly bind and cling to the chain to prevent it from being drawn therethrough too readily.

This ball is provided with an eye 20 on its 95 outer surface, said eye being set to one side of and at an angle to the axis of the hole 19, and the end 17 of the chain is connected to this eye, whereby when a strain is applied the ball is swung around so as to 100 cramp and bind the chain which passes through the hole preventing the chain from slipping, and when it is desired to slide the ball along the chain for the purpose of ad-

justment, it is only necessary to swing the ball around so that the axis of the hole is substantially in line with the chain when the ball may be readily slid along to readily obtain the required adjustment.

I claim:

The combination with a neck chain having a ring at one end and a portion of the chain looped through said ring and doubled back upon itself, of a binding member having a single opening through which a portion of this chain is passed, and an attach-

ing ring on said member disposed at an angle to the axis of said opening and to which the folded end of the chain is connected, 15 whereby the angular pull when under tension causes said member to effect a binding action upon the chain.

In testimony whereof I affix my signature in presence of two witnesses.

ERNEST J. QVARNSTROM.
